HONING DEVICE

Henry T. Wendt, Hannibal, Mo.

Application March 8, 1939, Serial No. 260,611

3 Claims. (Cl. 51—184.1)

My invention relates to improvements in honing devices for polishing the inner peripheries of the brake drums of automobiles.

As is well known, brake drums are turned to true the same on lathes generally speaking of two types, in one of which the drum is held stationary by a work holder and a tool revolved around the inner periphery thereof by a revolving tool holder, whereas, in the other type the tool holder is stationary and the drum revolved by the work holder about the tool. In both types, the tool holder is adjustable longitudinally of the lathe into the drum and laterally of the lathe to position the tool against the wall of the drum.

15 The instant invention is designed with the particular purpose in view of equipping such lathes with an inexpensive, highly efficient honing device for polishing the inner periphery of the drum after turning and which is adapted to be attached 20 to the tool holder of such lathes for work upon brake drums of different sizes without necessitating any change in the lathes.

Another object is to provide a honing device for the purpose above set forth adapted to engage the periphery of the drum at two circumferentially spaced points to perform, in effect, successive honing operations substantially concurrently.

Still another object is to provide a device for 30 effecting such successive honing operations which is adapted for compensating adjustment automatically to maintain the same honing pressures in operation on drums of different sizes.

To the accomplishment of the foregoing, and 35 subordinate objects presently appearing, a preferred embodiment of my invention has been illustrated in the accompanying drawing, set forth in detail in the succeeding description, and defined in the claims appended hereto.

40 In said drawing:

Figure 1 is a view partly in elevation and partly in transverse section illustrating my improved honing device applied to the tool holder of a lathe and in operative relation to the brake drum.

45 Figure 2 is a view in longitudinal section, parts shown in elevation, of the honing device detached and drawn to an enlarged scale.

Figure 3 is a detail view in transverse section taken on the line 3—3 of Figure 2 looking in the 50 direction indicated by the arrows.

Figure 4 is a view in plan of the hone carrier, and

Figure 5 is a similar view of the driving head.

Referring now to the drawing by numerals, the 55 type of lathe illustrated therein is that in which

the tool holder revolves relative to the drum and is adapted to be adjusted to feed the tool holder into and out of the drum and across the same. Only those parts of the lathe essential to a proper understanding of the invention have been illustrated, 4 designating the usual splined shaft for adjusting the tool holder 2 into and out of the drum 3 to be revolved in the direction of the arrow around said shaft by the usual gear drive, (not shown) the tool holder 2 embodying the 10 socket 5, the shank 6 slidably adjustable in the socket transversely of the axis of rotation thereof under manipulation of the screw feed 7, and the bit or tool holding arm 8 adjustably mounted in one end of the shank 6 at a right angle thereto 15 and provided with the socket end 9 with a set screw 10 thereon for clamping the usual bit or tool in said end. The work holder, or chuck, for the drum together with other parts of the lathe being well known and understood in the art have 20 not been illustrated and need not be referred to herein.

The honing device of my invention comprises an arcuate hone carrier 11 of bar-like form and any suitable metal provided in the outer convex 25 face thereof with a pair of transversely extending grooves 12 adjacent opposite ends thereof, respectively, said grooves being transversely square. A pair of hone sockets 13 of channel form and thin resilient metal are fitted into said 30 grooves 12, respectively, and detachably secured therein by screw bolts 14, a pair of which are threaded into said carrier 11 from the inner concaved side thereof and into the bottoms of said 35 sockets. A pair of bar-like flat hones 15 of suitable abrasive material are seated in said sockets 13 to extend outwardly therefrom and are clamped between the side walls of said sockets, said side walls having a press fit in the grooves 12 whereby they are clampingly engaged with said 40 hones. As will hereinafter more clearly appear, the hone carrier 11 is designed to be revolved endwise in the drum 3 in a direction whereby one hone constitutes a leading hone and the other a 45 trailing one. The hones 15 will hereinafter be referred to as leading and trailing hones.

The described hone carrier 11 is mounted on a substantially T-shaped shorter driving head 15' of bar-like metal, and by means of the following. A pair of stud bolts 16 are extended through said head 15' adjacent opposite ends thereof, respectively, with the tail ends thereof threaded into the concaved inner side of the carrier 11 upon opposite sides of the trailing hone 15, respectively, in the longitudinal center of said carrier. A pair 55

of cushion springs 17 are sleeved onto said bolts 16 intermediate said head 15' and carrier 11 and a pair of similar springs 18 are similarly disposed on said bolts 16 intermediate said head 15' and 5 the head ends of said bolts. The springs 17 and 18 balance the carrier 11 on the head 15'. As will be seen, by the described arrangement of the bolts 16 relative to the carrier 11, one bolt constitutes a leading one and the other a trailing one. 10 The trailing bolt 16 has a sliding pivotal fit in the head 15' and the leading bolt 16 passes through a slot 19 in said head. By this arrangement the trailing bolt 16 constitutes a driving coupling between the head 15' and carrier 11 and 15 said carrier and trailing bolt are adapted for yielding pivotal movement on said head 15' as will be clear.

The head 15' is mounted on the end of a shank 20 to swivel thereon and by means of a socket 21 20 in the end of the stem 22 of said head 15' which receives a ball 23 on one end of said shank. The shank 20 has an enlarged squared part 24 adapted to fit into the socket end 9 of arm 8 to be clamped therein by the set screw 10. A set screw 25 25 threaded into the stem 22 of the head 15' provides for taking up wear between the described ball and socket joint. A slot 26 is provided in the head 15' for access with a screw driver to the screw bolt 14 that secures the socket 13 of the 30 trailing hone 15 to the carrier 11.

Referring now to the operation, with the shank 20 positioned in the tool holder 2 in the manner already described, the honing device is moved into the drum 3 by adjusting the splined shaft 1 35 and then toward the inner periphery of the drum 3 by adjustment of the holder 2 under manipulation of the screw feed 7 until the hones 15 engage the inner periphery of said drum and the springs 17 are compressed so as to yieldingly 40 thrust said hones 15 against said periphery with the desired pressure. As will be readily apparent, the carrier 11 and head 15' may pivot freely on the shank 20 universally to engage the hones 15 flush with the inner periphery of the drum 3. 45 Under revolving movement of the tool holder 2 the leading and trailing hones 15 successively polish the periphery of the drum in a manner which will be understood.

Under outward thrust of the described honing 50 device against the periphery of the drum 3 and since the line of thrust is axial of the shank 20 and, therefore, closer to the trailing hone 15 than to the leading hone, said trailing hone will be forced against the periphery of the drum 13 and 55 fulcrumed thereagainst to force the leading hone against said periphery with less pressure than that exerted by said trailing hone. Thus honing under different degrees of pressure is effected, the leading hone performing a preliminary light 60 polishing operation and the trailing hone a finishing operation under greater pressure. The described ball and socket joint 21, 23 provides for

compensating movement of the carrier 11 and head 15' to adjust the hones 15 automatically against drums of different sizes as will be understood from the foregoing.

The construction, operation and advantages of 5 the invention will, it is believed, be readily understood from the foregoing without further explanation.

Manifestly the invention, as described, is susceptible of modification without departing from 10 the inventive concept and right is herein reserved to such modifications as fall within the scope of the subjoined claims.

What I claim is:

1. In a machine for polishing a brake drum 15 mounted thereon, a tool holder adjustable in the drum crosswise thereof, and a tool comprising a shank mounted in said holder, a head mounted on said shank for universal pivotal movement thereon, a hone carrier yieldingly mounted on 20 said head and of elongated arcuate form, and a pair of flat bar-like hones mounted upon said carrier adjacent opposite ends thereof to be thrust against the inner periphery of said drum under crosswise adjustment of said holder. 25

2. In a machine for polishing a brake drum mounted thereon, a tool holder rotatable in the drum and adjustable crosswise thereof, a tool comprising a bar-like head, means to mount said head on said holder for universal pivotal movement and rotation endwise in said drum under rotation of said holder, a bar-like tool carrier of 30 arcuate form, means to mount said carrier on said head for rotation endwise therewith and for yielding movement thereon, and a pair of leading and trailing hones mounted on said carrier adjacent opposite ends thereof, respectively, to be 35 yieldingly thrust against the inner periphery of said drum under crosswise adjustment of said holder. 40

3. In a machine for polishing a brake drum mounted thereon, a tool holder rotatable in said drum and adjustable crosswise thereof, a tool comprising a shank mounted in said holder, a T-shaped driving head of elongated form having 45 a central boss pivotally mounted on said shank for universal swinging movement of the head on said shank and for rotation endwise in said drum, an arcuate bar-like hone carrier, means to mount said carrier on said head for rotation endwise 50 thereby, and a pair of leading and trailing hones mounted on said carrier adjacent opposite ends thereof, respectively, said means comprising a pair of bolts slidably extending through said head adjacent opposite ends thereof, respectively, and 55 threaded into said carrier upon opposite sides of said trailing hone, respectively, in the longitudinal center of said carrier, tension springs on said bolts intermediate said carrier and head, and similar springs on said bolts intermediate the free 60 ends thereof and said head. 55

HENRY T. WENDT.
